(57) **CLAIM**

The ornamental design for a battery box for an agricultural vehicle, as shown and described.

DESCRIPTION

FIG. 1 is a top perspective view of a battery box for an agricultural vehicle embodying our new design;

FIG. 2 is a rear perspective view thereof;

FIG. 3 is a front view thereof;

FIG. 4 is a side view thereof; and,

FIG. 5 is a rear view thereof.

The broken line representations in the figures show unclaimed environment or boundaries, and thus form no part of the claimed design.

The nature of this product is a battery box for an agricultural vehicle, such as a tractor.
